UNITED STATES PATENT OFFICE.

CHARLES T. SCHOEN, OF PHILADELPHIA, PENNSYLVANIA, ASSIGNOR TO
THE CHARLES SCOTT SPRING COMPANY, OF SAME PLACE.

CAR-SPRING.

SPECIFICATION forming part of Letters Patent No. 378,264, dated February 21, 1888.

Application filed July 25, 1887. Serial No. 245,231. (No model.)

To all whom it may concern:

Be it known that I, CHARLES T. SCHOEN, a resident of Philadelphia, Pennsylvania, and a citizen of the United States, have invented certain Improvements in Car-Springs, of which the following is a specification.

My invention relates to that class of car-springs in which the plates are made of wrought metal.

10 Heretofore in the construction of these wrought-metal car-spring plates it has always been necessary to employ in connection with one of the plates a separate deep socket, in order to allow for the free movement of the connecting bolt or bolts on compression of the springs, as shown, for instance, in Fig. 10 of the drawings of Letters Patent No. 368,428, dated August 18, 1887, granted for my improvements in car-springs. The construction of car-springs having wrought-metal plates with the separate sockets is, however, lacking in economy and in strength and security of the car-springs. I have found that these separate sockets can be dispensed with and their accompanying objections overcome by punching, drawing, or forcing up deep recesses or sockets in the bodies of both top and bottom plates, which recesses jointly are of sufficient depth to permit the desired full movement of the confining bolts. 25 Heretofore it has been customary to form in one of the wrought-metal plates shallow recesses sufficient merely for the reception of the bolt-heads or nuts on the bolts; but the formation of recesses in the spring-plates themselves 30 of sufficient depth for the full play of the bolts has heretofore been considered an impossibility and the objectionable separate sockets considered a necessity.

In the accompanying drawings, Figure 1 is 40 vertical section of a car-spring constructed in accordance with my invention. Fig. 2 is a plan view of the same, and Fig. 3 is a plan view of a car-spring of a modified form. Figs. 4 to 9, inclusive, are views illustrating successive 45 steps in the formation of a car-spring plate in accordance with my invention.

In Figs. 1 and 2 I have illustrated a car-spring of the character known as a "graduated" car-spring, there being two end spirals, 50 B B, pressing against and confined between the

top and bottom plates, A and A', with an intermediate spiral, B', of larger diameter occupying the space between the end spirals and confined in position by the flanged edges *a* of the top and bottom plates, but not pressing against the said top plate until the load on the car-spring is such as to compress the end spirals, B B, to a certain extent.

In Fig. 3 I have illustrated in plan view a modified form of car-spring in which three 60 spirals are to be used, as will be readily understood without detailed explanation. I do not, however, wish to confine myself to either of these particular shapes or styles of car-springs, as my invention may be applied to various constructions of car-springs in which the spirals are confined between top and bottom plates of wrought metal.

D D are the confining bolts, which hold the top and bottom plates, A A', together, each 70 bolt having at one end a suitable head, *d*, and at the other end a nut, *d'*. In order to allow space not only for these heads and nuts, but also for the free play of the bolts as the springs are compressed, I form in the top as well as 75 the bottom plates deep sockets or recesses E, the recesses in each plate being of a sufficient depth to allow for the head or nut of each bolt, and also for one-half of the movement due to complete compression of the springs under 80 load.

In order to punch, press up, draw, or otherwise form these sockets the more readily without injury to the metal of which the plate is made, I make the walls of the sockets of the 85 curved form illustrated in Fig. 1. Furthermore, since each plate has its sockets formed of a depth to allow for one-half of the movement due to compression of the springs, both top and bottom plates may be made precisely alike, 90 and therefore only one set of dies will be needed for their formation, whereas car-springs with wrought-metal plates and separate sockets require separate sets of dies for the top and bottom plates.

At the same time that the sockets E E as well as the flange *a* are formed on each plate and by the same dies I prefer to draw, punch, or press up to the outer side of the plate projecting teats F, to be adapted to corresponding re- 100

cesses in the wood or iron work of the car to hold the car-spring boxes in position.

In pressing up car-spring plates in accordance with my invention it is necessary to effect the formation of the deep sockets by a series of operations, in order to prevent excessive strain upon the plates. Thus, as shown in Figs. 4 to 9, the blank is first punched out, as shown in Figs. 4 and 5, the first pressing operation effecting the formation of the lugs F and striking up large and comparatively shallow pockets from the plate, as shown in Figs. 6 and 7, while the second operation effects the flanging of the edges of the plate, the deepening of the sockets, and the contraction of the upper portions or mouths of the same.

I claim as my invention—

1. A car-spring having wrought-metal plates with deep sockets drawn or pressed up out of the bodies of the plates of a depth to allow for the full movement of the bolts on compression

of the springs under load, substantially as set forth.

2. A car-spring having its top and bottom plates of wrought metal precisely alike, with deep sockets drawn or pressed up out of the body of the metal, the sockets in both plates being jointly of a depth to allow the full movement of the bolts on compression of the springs under load, substantially as described.

3. A car-spring plate of wrought metal having deep sockets pressed or drawn up out of the body of the metal, with their walls of a curved shape, substantially as and for the purpose described.

In testimony whereof I have signed my name to this specification in the presence of two subscribing witnesses.

CHAS. T. SCHOEN.
